UNITED STATES PATENT OFFICE.

KINDERMAN M. BOBLETT, OF TOLEDO, OHIO.

METAL-BENDER.

1,118,770.

Specification of Letters Patent. Patented Nov. 17, 1914.

Application filed December 17, 1912. Serial No. 737,247.

To all whom it may concern:

Be it known that I, KINDERMAN M. BOBLETT, a citizen of the United States, residing at Toledo, in the county of Lucas and State of Ohio, have invented certain new and useful Improvements in Metal-Benders, of which the following is a specification.

My invention relates to metal forming apparatus and particularly to a metal bending machine designed to produce from a single flat sheet of material a cellular body comprising a succession of oppositely disposed flat sided loops or bights.

The object of the invention is to provide a metal bending apparatus which will be simple in structure as well as in means and mode of operation, whereby it not only may be economically manufactured but will be more efficient in use, automatic in its operation, rapid in its production, capable of being operated by unskilled labor and unlikely to get out of repair.

With the above primary and other incidental objects in view as will more fully appear in the specification, the invention consists in the features of construction, the parts and combinations thereof and the mode of operation or their equivalents as hereinafter described and set forth in the claims.

Referring to the drawings, Figure 1 is a front elevation of a stamp or punch press to which the metal bending apparatus has been applied. Fig. 2 is a side elevation of the stamp press with metal bending apparatus applied thereto. Fig. 3 is a plan view of the metal bending apparatus removed from the press. Fig. 4 is a detail plan view of the mandrel carrying heads and the means for shifting said heads to and from operative positions, the mandrels being shown in their outermost or inoperative positions. Fig. 5 is a side elevation of the mandrel carrying heads with the mandrels in their inward or operative positions. Fig. 6 is an end elevation of one of the mandrel carrying heads. Figs. 7 and 8 are detail views of a pair of mandrel carrying heads, Fig. 7 showing the oscillating mandrels in their lowermost position while in Fig. 8 the oscillating mandrels have been oscillated to their elevated or operated positions. Fig. 9 is a detail side elevation of the mandrel oscillating mechanism. Fig. 10 is a detail view somewhat diagrammatic illustrating successive steps in the formation of the

product. Fig. 11 is a detail perspective view of the die body. Fig. 12 is a perspective view of the product. Fig. 13 is a diagram defining the cycle of operation with relation to the rotation of the fly wheel or main drive shaft. Fig. 14 is a composite diagram of the various steps in the performance of the work, successive positions being shown by solid lines, dotted lines and dot and dash lines respectively.

Like parts are indicated by similar characters of reference throughout the several views.

The bending apparatus forming the subject matter hereof is designed to produce from a flat sheet of metal, a cellular body such as is illustrated in Fig. 12 and as fully set forth and described in my co-pending application Serial No. 687,619 filed April 1, 1912, for improvements in radiators.

The cellular body as shown in Fig. 12 comprises a succession of oppositely disposed flat sided loops or bights or cellular spaces 1—1, the opposite sides of which are indented or recessed intermediate their ends 2 as indicated at 2, such recessed portion being provided with a longitudinally disposed groove or depression 3.

It will be obvious that the apparatus is not confined to the production of a body exactly as shown in Fig. 12, but the recess 2 and depression 3 may be omitted from the side of the loop or bight or other surface configurations might be substituted therefor. Also loops of different shapes might be produced.

In the drawings, the invention has been shown as applied to a punch or stamp press of ordinary construction which forms no part, *per se*, of the present invention. This stamp press comprises a main frame 4 in which is mounted a vertically reciprocating plunger head 5 actuated by a drive shaft 6 journaled in the upper portion of the main frame 4. The drive shaft 6 carries at one end a pulley or fly wheel 7 and at its opposite end two cranks or wrist pins 8 and 9.

Secured upon the bed plate 10 of the stamp press is the base plate 11 of the bending apparatus. Journaled in pendant bearings 12 projecting from the under side of the base plate 11 adjacent to one end thereof is a transverse hollow rock shaft 13 carrying two radially disposed arms 14 and 15. Journaled within the hollow rock shaft 13 is 110

a second rock shaft 16 provided with a radially disposed arm 17. A pitman or link 18 connects the crank or wrist pin 8 of the drive shaft 6 with the arm 17 of the rock shaft 16. 5 A similar pitman or link 19 connects the crank or wrist pin 9 with the radial arm 14 of the hollow rock shaft 13. The connection of the pitmen 18 and 19 with the wrist pins 8 and 9 is preferably by a double pivotal joint as indicated at 20. This connection permits of a more or less universal movement of the pitman to compensate for the rotation of the connected parts about axes arranged at right angles to each other. 15 Carried upon the plunger head 5 of the press is a punch 21 co-acting with a die 22 supported upon the base plate 11, (shown in detail in Fig. 11). The die 22 comprises a block having an off-set or step 23 therein 20 and provided with lateral flanges 24. The upper plane of the offset block is provided with a reciprocating plate 25 coincident with the offset or step 23. The reciprocating plate 25 is provided with laterally projecting 25 arms 26 carrying at their outer extremities rollers 27 projecting from the lateral faces of the die block 22. These projecting rollers 27 are engaged by cam fingers 28 carried by the plunger head 5 and projecting on opposite sides of the die block 22, to reciprocate the plate 25 forward beyond the offset or step 23 against the tension of its retracting spring 29 as the plunger head and punch move upward. This 30 reciprocal movement of the plate 25 serves to advance the finished product and section of the material across the die as hereinafter described. The lower plane of the die block 22 is provided intermediate 35 of its side flanges 24 with a raised portion 30, corresponding to the depression 2 of the product, upon which the finished product is supported.

Projecting upward from the surface of 40 the lower plane of the die block adjacent to the off-set or step 23 and parallel therewith are two ribs or beads 31 corresponding to the grooved depression 3 of the product which they co-operate with the punch to 45 produce as hereinafter mentioned. These beads or ribs 31 produce the grooved depression 3 in the under side of the product, while corresponding ribs or beads 32 carried upon the punch 21 produce similar 50 grooved depressions on the upper side of the product.

Mounted in gibbed ways or guides 55 upon the upper face of the base plate 11 are sliding mandrel carrying heads 34. The heads 34 reciprocate to and from each other in the guides or ways 33 in a direction at right angles to the path of travel of the material and product across the die block 22. The sliding heads 34 terminate at their 60 adjacent ends in extensions 35 in which

are secured two fixed mandrels 36. The mandrels 36 are shaped in cross section to conform to the interior of the cellular spaces 1 of the product within which they are adapted to project to a medial point. The 70 mandrels 36 are spaced one from the other a distance substantially equal to the thickness of the metal operated upon, while each is provided on its outer face with a longitudinal groove 37 corresponding with the 75 groove depression 3 of the product and a shoulder 38 adjacent to the support 35 corresponding to the raised portion of the product at opposite sides of the depression 2. It will be understood that the oppositely disposed mandrels 36 carried by the 80 opposing heads 34 when projected to a meeting point within the cellular spaces 1 will completely fill such spaces. The longitudinal 85 grooves 37 in the under side of the mandrels 36 register with the corresponding rib or bead 31 of the die, while those of the upper side register with the bead 32 of the punch.

To reciprocate the mandrel carrying 90 heads to and from each other to cause the mandrels 36 to be inserted into and withdrawn from the cellular spaces 1 of the product, there is provided upon the base plate 11 beneath the die 22 and intermediate 95 the guides or ways 33 of the sliding heads 34 a reciprocating cam plate 40 having converging cam grooves 41 therein. Each of the sliding heads 34 is provided with an inward projecting arm 42 carrying a roller 43 which engages in one of the cam grooves 41. A link or pitman 44 connects the reciprocating cam plate 40 with the radial arm 15 of the hollow rock shaft 13. As the drive shaft 6 is rotated, motion is transmitted through the pitman 19 to the hollow rock shaft 13 causing an oscillatory movement thereof which movement is transmitted through the radial arm 15 and the link or pitman 44 to the cam plate 40 causing 110 a reciprocatory movement of the latter. As the cam plate 40 reciprocates, the engagement of the rollers 43 within the inclined cam grooves 41 causes the mandrel carrying heads 34 to be simultaneously reciprocated to or from each other according to the direction of movement of the cam plate 40. 115

Journaled in uprights forming portions of each of the mandrel carrying heads 34 is a rock shaft 45 upon which is secured 120 an elongated gear member 46 having the form of a corrugated cylinder, the corrugations of which comprise gear teeth. At its inner extremity the rock shaft 45 terminates in an oscillatory head 47 operating 125 in a plane coincident with the extension 35 and adjacent thereto.

A pair of mandrels 48 are carried by each oscillatory head 47. These mandrels 48 are counterparts of the mandrels 36. They are 130

separated one from the other by an intermediate space substantially equal to the thickness of the material operated upon and each is provided on its outer face with a longitudinal groove 49 corresponding to the grooved depression 3 of the product and registering with one of the beads or ribs 31 of the die block on the under side and with the corresponding bead or ribs 32 of the punch at the upper side. Each mandrel 48 is also provided upon its outer face with a shoulder 50 corresponding with a similar shoulder 38 of the mandrels 36 and with the raised portion of the product at either side of the depression 2. The mandrels 48 are rotated through an arc of 90 degrees from a recumbent position as shown in Fig. 7 to an upright position adjacent to the fixed mandrels 36 as shown in Fig. 8.

The mandrels 48 are so located in the oscillatory head that the exterior corner 51 of one of the mandrels will coincide with the axis of the rock shaft 45. The relation of the parts is such that the oscillation of the shaft 45 and mandrels 48 carried thereby will not change the position of the axial corner 51, but the two mandrels 48 will be turned about said corner line as the center.

To oscillate the mandrels 48 throughout the quarter turn as described, there are provided upon the rock shaft 16 adjacent to each end thereof, gear sectors 52. Mounted to slide in suitable guides or keepers 53 and 54 are reciprocatory rack bars 55 engaging the gear sectors 52 at one extremity and the cylindrical gears 46 at the opposite extremity. The guides 53 are stationarily secured upon the ways or guides 33 in which the mandrel carrying heads 44 reciprocate. The guides 53 are loosely supported upon the actuating shaft 16. The guide or keeper 54 being fixed in its position and engaging the opposite sides of the rack bar 55, prevents lateral movement of the latter as the mandrel carrying head 44 is reciprocated. The elongated or cylindrical gears 46 permit the mandrel carrying heads to be adjusted throughout the full limit of their strokes while maintaining operative engagement with the rack bars 55. Upon the reciprocatory movement of the mandrel carrying heads 44 the teeth of the cylindrical gear 46 slide longitudinally between the teeth of the rack bar 55, thereby maintaining at all times operative engagement by which the cylindrical gears 46 of the heads 44 and mandrels 48 may be rotated by the reciprocatory movement of the rack bars. As before stated, the rack bars are reciprocated by the action of the sectors 52 carried upon the rock shaft 16 which are oscillated by the rotation of the drive shaft 6 transmitted through the pitman 18 to the radial arm 17 upon said rock shaft 16.

The several parts of the operating mechanism being assembled as shown in the drawings and operatively connected to perform the cycle of operation in the sequence and at the time indicated upon the diagram 70 in Fig. 13, the operation of the apparatus is as follows: It is to be noted that the punch is provided with an offset or shoulder 56 co-operating with the offset or step 23 of the die block 22 and a second offset or shoulder 57 upon which the ribs or beads 32 are carried co-operating with the movable mandrels 48 to form the sheet of metal when the punch is depressed. At the beginning of the operation the punch being 75 in elevated position, the sheet of material extends from the upper plane of the die block to the last uncompleted loop or bight formed about the uppermost mandrel 48 as shown in stage *a*, Fig. 10. As the punch 80 descends, the pendant portion thereof intermediate the shoulders 56 and 57 enters between the offset or step 23 of the die block and the movable mandrels 48 carrying with it a portion of the sheet of unformed metal 85 and forming therein a substantially rectangular U shaped bight as clearly shown at stage *a* in Fig. 10. At the same time the beads or ribs 32 upon the punch shoulder 57 drive the metal bent over the tops of the 90 mandrels into the corresponding longitudinal grooves 49 and 37. At the same time offset portions 58 at each side of the shoulder 57 of the punch entering between the shoulders 50-50 and 38-38 of the opposing mandrels, carried by the opposite mandrel carrying heads form the intermediate depression 2 in the product. The punch is then withdrawn upward out of engagement 95 with the metal and die as shown in stage *b*, Fig. 10. At the same time the mandrels 36 and 48 are withdrawn from the loops or bights formed in the product by the outward reciprocation of the mandrel carrying heads 44 due to the reciprocatory movement of the cam plate 40 actuated by an oscillation of the hollow shaft 13. The pendant fingers 28 carried by the plunger head 5 engage the rollers 27 of the reciprocating feeding plate 25 and reciprocate said 100 plate against the tension of its retracting spring 29. The reciprocating feeding plate 25 engaging the offset formed in the sheet of metal advances the finished product and the strip of unformed metal upon the die 105 block a distance equal to one cellular space. Such advance step of the metal is indicated by dotted lines in stage *b*, Fig. 10. It is to be understood that the mandrels 36 and 48 have been entirely withdrawn in opposite 110 directions from the work prior to the shifting movement of the feed plate 25. Upon the initial downward movement of the plunger, the cam faces of the fingers 28 disengage the rollers 27 of the feed plate, per 115

120

125

130

mitting the feed plate to be retracted by the action of its spring 29 whereupon the mandrel carrying heads 34 are reciprocated inward toward each other by the reciprocatory movement of the cam plate 40. However, before being reciprocated inward the oscillating mandrels 48 have been swung downward to a recumbent position such as is shown in Fig. 7 by the reciprocatory movement of the rack bars 55 due to oscillatory movement of shaft 16.

As the mandrel carrying heads move inward, the mandrels 36 enter within the superimposed loops or cellular spaces last formed while the recumbent mandrels 48 will enter upon opposite sides of the offset formed in the sheet of metal as shown at stage *c* Fig. 10. The several mandrels having been reciprocated inward until the mandrels have entered the work and meet at the medial line thereof, the cylindrical gears 46 and oscillating mandrels 48 are rotated through a quarter turn by the reciprocatory movement of the rack bars 55, oscillating the mandrels 48 upon the corner 50 as an axis. This oscillatory movement of the mandrels 48 carries with them the engaged portion of the strip of metal causing given points upon the strip of metal to move through arcuate paths as indicated by darts in stage *c*, Fig. 10, to corresponding positions with the mandrels in upright position, whereby the strip of metal will be wrapped entirely about the lowermost mandrels 48 and about three sides of the upper mandrels 48, assuming the position as shown in stage *d*, Fig. 10. As the mandrels 48 are rotated, the longitudinal groove 49 of the lowermost mandrel 48 registers with one of the beads 40 or ribs 31 of the die block forming on the under side of the product the longitudinal depression 3, while the shoulders 50 of the mandrels 48 co-act with the die block to form the intermediate depressions 2 in the work. The next step in the operation is the descent of the punch to form a succeeding rectangular U shaped bend in the sheet of metal, thereby completing the loop about the uppermost mandrels 48 and so completing the cellular spaces. This cycle of operation is successively repeated until a cellular body of the desired length is attained. The second bead or rib 31 upon the die block insures the proper registration of the work with the die after each advance step.

From the above description it will be apparent that there has thus been produced a machine of the character described, possessing the particular features of advantage before enumerated as desirable, but which obviously is susceptible of modification in its form, proportions, detail construction and arrangement of parts without departing from the principle involved or sacrificing any of its advantages.

While, in order to comply with the statute, the invention has been herein described in language more or less specific as to certain structural features, it is to be understood that the invention is not limited to such specific details, but that the means and mechanism herein shown and described comprise but one mode of putting the invention into effect, and the invention is therefore claimed broadly in any of its possible embodiments or modifications within the scope of the appended claims.

Having thus described my invention, I claim—

1. In a bending apparatus, a reciprocatory bending member for forming in a continuous strip of material a U shaped bight, one side of which is of greater length than the other, and an oscillating member for bending the transverse portion of the bight the construction and arrangement being such that the extremity of the short side of the bight will be brought into proximity to the long side to inclose a cellular space, substantially as specified.

2. In an apparatus for bending a continuous strip of material into a cellular body, a bifurcated mandrel through the bifurcation of which the material to be operated upon extends, means for causing the material at opposite sides of the mandrel to be wrapped in opposite directions about said bifurcated mandrel and pressure means for setting the material into conformity with the mandrel.

3. In a bending apparatus, a forming member adapted to form in a strip of material a U shaped bight, and a bending member adapted to bend the transverse portion of the bight, whereby one side of the bight will be brought to a position angular with the opposite side of the bight, and means for alternately operating the forming member and bending member.

4. In an apparatus for forming a continuous strip of material into a cellular body, a movable mandrel and a relatively fixed mandrel to and from which the first mentioned mandrel is movable, means for engaging the relatively fixed mandrel in a previously formed cellular space and to subsequently shift the movable mandrel while engaged with the material operated upon to form a succeeding cellular space to be subsequently engaged by the relatively fixed mandrel.

5. In an apparatus for forming a continuous strip of material into a cellular body, a movable head, two mandrels carried thereon in parallel relation and adapted to be moved into and out of engagement with the material operated upon by the movement of the head, one of the mandrels being capable of oscillatory movement to and from the other mandrel, and means to os-

- 5 cillate the oscillatory mandrel, the construction and arrangement being such that at each operative movement of the head the relatively fixed mandrel will be projected into a previously formed cellular space and the oscillatory mandrel will be projected into engagement with the work and thereafter oscillated to wrap the material thereabout to form a new cellular space.
- 10 6. In an apparatus for forming a continuous strip of material into a cellular body, a reciprocatory mandrel about which the material is shaped to form a cellular space, means for reciprocating the mandrel into and out of engagement with the work and means to advance the work upon each retrograde movement of the mandrel.
- 15 7. In an apparatus for forming a cellular body, a mandrel capable of reciprocatory and rotary movement, a punch and die, means to reciprocate the mandrel to a position intermediate the punch and die and to subsequently rotate the mandrel, substantially as described.
- 20 8. In an apparatus for forming a cellular body, a punch, a die, a bifurcated mandrel adapted to engage the strip of material operated upon within the bifurcation thereof, means to rotate the mandrel to bend the strip into a substantially S shape about the fingers of said mandrel, the punch being adapted to pass adjacent to the mandrel and to bend the adjacent portion of the strip to parallelism with the side of the mandrel
- 25 30 35 to complete a figure 8 formation of the strip about the fingers of the mandrel, substantially as specified.
9. In an apparatus for forming a cellular body, a punch, two reciprocatory mandrels, one of the mandrels being capable of an oscillatory movement in addition to its reciprocatory movement, the non-oscillatory mandrel being projected into a previously formed cell by its reciprocatory movement, the oscillatory movement of the other mandrel being adapted to bend the strip of material about the mandrel to form a succeeding cell, said punch operating to set the metal in its bended form, substantially as
- 40 45 50 specified.
10. In an apparatus for forming a continuous strip of material into a cellular body, a reciprocatory mandrel, a forming member by which the material is pressed into conformity with the mandrel, the continuous strip of material being offset by the forming operation, means to reciprocate the mandrel and a feeding member engaging the offset in the material to advance the work upon the withdrawal of the mandrel from engagement therewith.
- 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 18. In an apparatus for forming a continuous strip of material into a cellular body, means for offsetting the strip of material, a bending member adapted to bend the material and a feeding member engaging the offset to advance the material to position to be operated upon by the bending member. 65
19. In a bending apparatus, a forming member adapted to bend the material operated upon, oppositely disposed oscillatory mandrels about which the material is bent, means for reciprocating the oscillatory mandrels to and from each other, and means for simultaneously oscillating the mandrels, substantially as specified. 70
20. In a metal forming apparatus, an offset die, a forming member cooperating with the offset die to form an offset in the strip of material, and a reciprocating feeding member actuated by the retrograde movement of the forming member to engage the offset formed in the strip to advance the strip preparatory to the next operation. 75
21. In a bending apparatus, an elongated reciprocating gear, an oscillatory bending member carried thereby, a reciprocating rack meshing with the gear and adapted by its reciprocating movement to rotate the gear, in relation with which the gear is longitudinally adjustable while maintaining operative engagement therewith, the construction and arrangement being such that the bending member will be moved into and out of engagement with the work by the reciprocating movement of the gear and will be oscillated while in engagement with the work by the oscillatory movement of the gear due to the reciprocating movement of the rack. 80
22. In a bending apparatus, an oscillatory mandrel revoluble about an eccentric axis, means for engaging the mandrel with the work while positioned at one extremity of its oscillatory movement, means for oscillating the mandrel about its eccentric axis while engaged with the work to wrap the work thereabout, and a forming member engaging the work at the opposite limit of oscillatory movement of the mandrel to press the material into conformity with the mandrel. 85
23. In a bending apparatus, a bifurcated oscillatory mandrel the bifurcation of which is offset in relation with the axis of oscillation, means for engaging the material operated upon in said bifurcation, means for oscillating the mandrel, and means for pressing the material into engagement with the mandrel. 90
24. In a bending apparatus, an oscillatory mandrel, means for engaging the mandrel with the work, means for rolling the mandrel in a lineal direction, a partial re- 95
- lation while engaged with the work to wrap the material thereabout. 100
25. In a bending apparatus, a punch press, means for advancing the work, two oppositely disposed reciprocating heads, means for reciprocating the heads to and from each other, an oscillatory mandrel and a fixed mandrel carried by each of the heads, said fixed mandrels being adapted to project from opposite sides of the work with- 105
- in a recess previously formed in the work when the heads are caused to approach each other, the oscillating mandrels being adapt- 110
- ed to engage the portion of the work to be operated upon upon the inward recipro- 115
- cation of the heads, and means to oscillate the oscillatory mandrels after being engaged with the work, said punch press serv- 120
- ing to set the portion of the work bended by the oscillation of the mandrels, substan- 125
- tially as specified. 130
26. In a bending apparatus, a bifurcated mandrel, means for causing the material to be operated upon to be engaged in the bifurcation of the mandrel, means for rotat- 135
- ing the mandrel to wrap the engaged por- 140
- tion of the material in opposite directions about the mandrel, and means for applying pressure to set the material so bended, sub- 145
- stantially as specified. 150
27. In a metal forming apparatus as de- 155
- scribed, a support for the work, having an unlined surface configuration, over which the material operated upon lies, an oscillatory forming member overlying the work having corresponding surface configura- 160
- tions registering with those of the work support when the oscillatory member is at one limit of its oscillatory movement, and means to oscillate the forming member to and fro in a lineal direction upon the work 165
- to shape the material to the registering configura- 170
- tions of the oscillatory member, and support. 175
28. In a bending apparatus, an oscilla- 180
- tory mandrel, means for engaging the man- 185
- drel with the work and means to roll the mandrel in a lineal direction while engaged with the work to wrap the material there- 190
- about. 195
29. In a metal forming apparatus, an os- 200
- cillatory mandrel adapted to be engaged with the material operated upon, means to roll the mandrel in a lineal direction while engaged with the material, a support for the material having surface configura- 205
- tions therein conforming to the mandrel. 210
30. In an apparatus of the character de- 215
- scribed, a rotary mandrel, and a second mandrel fixed in relation with the rotary mandrel, means for shaping the material around the rotary mandrel, means for en- 220
- gaging and disengaging said mandrels with the material the construction and arrange- 225

ment being such that the fixed mandrel will at each operation engage that portion of the work vacated by the rotary mandrel.

31. In an apparatus of the character described, a reciprocatory rack, an elongated gear engaged by the rack longitudinally movable in relation with the rack, a mandrel carried by the gear reciprocated into and out of engagement with the work by 10 the longitudinal movement of the gear in-

dependent of the rack, and oscillated by the rotary movement thereof under the influence of the rack.

In testimony whereof, I have hereunto set my hand this 9th day of December, 1912. 15

KINDERMAN M. BOBLETT.
